UNITED STATES PATENT OFFICE.

JOHN BASS, OF BOIS-COLOMBES, FRANCE.

GRINDING OF ANTIFRICTION-ROLLERS.

1,375,890.

Specification of Letters Patent. Patented Apr. 26, 1921.

Application filed March 2, 1918. Serial No. 220,003.

To all whom it may concern:

Be it known that I, JOHN BASS, a subject of the King of Great Britain, residing at 20 Rue Carnot, Bois-Colombes, Seine, in 5 the Republic of France, have invented certain new and useful Improvements in or Relating to the Grinding of Antifriction-Rollers, of which the following is a specification.

10 This invention relates to the grinding of antifriction rollers and has for its chief object to enable such rollers to be more uniformly and smoothly ground thereby producing true and cylindrical antifriction rollers or cylinders which in use will economize power, obviate irregularity of wear, remove the need for excessive lubrication, prevent the bearing with which they are employed from becoming unduly heated, and lessen or 20 prevent noise during the rolling action.

According to the present invention the rollers are subjected to an abrading action by means of a rotary cage adapted to carry them between grinding surfaces so that each 25 roller is also rotated about its axis during the rotation of the cage. Means are also provided whereby the rollers, during each revolution of the cage may be removed and returned thereto with their axes reversed.

30 In order that the invention may be clearly understood and readily carried into effect the same will now be more fully described by the aid of the accompanying drawing in which:—

35 Figure 1 is a fragmentary view of a roller or cylinder grinding machine.

Fig. 2 is a plan in part of Fig. 1.

Fig. 3 is a view of Fig. 1 as seen in the direction of the arrow x .

40 Figs. 4 and 5 are, respectively, edge and face views of the grinding surfaces and cage;

Fig. 6 is a sectional view taken on the line $x-x$ of Fig. 5;

45 Fig. 7 is a detail sectional view on an enlarged scale;

Fig. 8 is a sectional view and substantially on line $z-z$ of Fig. 5;

50 Figs. 9 and 10 are detail elevations of two of the parts.

Referring to the drawings:—

A, B, designate, respectively, the grinding wheel and disk, and C is the support or shaft on which the wheel A is mounted to 55 revolve while being capable of moving longitudinally thereof under pressure. The

non-rotating disk B, which is also adapted to slide on the support C, or the member C' thereof, is carried by a sleeve B' and the cage or ring α , support b and guide c , are 60 supported from the disk B so that these various members may be simultaneously moved longitudinally of the supporting shaft C toward or from the wheel A, as by means of a handwheel (not shown). The 65 shaft or support referred to is, as shown, preferably composed of two sections C, C', connected as shown in Fig. 6 to permit of the grinding wheel A, disk B and cage or ring α , being properly assembled. 70

The cage or ring α is provided with a series of openings α' for receiving the rollers during the grinding operation and is supported, as shown in Fig. 5, by four peripherally grooved wheels α^2 , two of which 75 are adjustably mounted on the disk B (Figs. 6 and 7) while the other two are supported on the member b (Figs. 5 and 8). Said cage or ring α may be composed of a plurality of sections or segments secured by screws to 80 a ring or hoop, as indicated in dotted lines in Fig. 5. The guide c is also supported from the member b by means of brackets d, d , (Figs. 4 and 5) and the cage or ring α is free to turn on the grooved wheels α^2 be-

tween the support b and guide c . Said guide c and support b are of the segmental form shown in Figs. 10 and 9 respectively. The cage or ring α (see Fig. 5) is arranged eccentrically to the axis of the grinding 90

wheel A and the disk B and the support b and guide c are arranged in such relation to the cage or ring α that they serve to prevent the rollers falling from the cage or ring when not in contact with the grinding wheel 95

A and disk B. The support is connected to the disk B by the members B^2 and is provided with openings or slots b', b^2 (Fig. 9), whereby the rollers may pass from and return to the cage or ring during the grinding operation. Adjacent the slot B' are inclined projections e', e^2 (see Fig. 1) mounted, respectively, on the guide c and support b , whereby as the rollers approach the slot 100

b' , they are caused to leave the cage α and pass through the slot b' into the spiral or twisted conduit f carried by the support b ,

which conduit causes the rollers as they pass therethrough to turn in the direction of their length. The conduit is slightly inclined and 105 provided at its lower end with a hopper g into which the rollers pass on leaving the

110

115

120

spiral conduit. The hopper or chute *g* connects by means of an inclined trough *h* to the support *b* adjacent the slot or opening *b*² through which the rollers in their reverted positions pass into or reenter the cage *a*. The hopper *g* and trough *h* are such as to allow of the rollers being mixed and caused under the action of gravity to move toward the opening *b*², while to feed the rollers through the opening a belt *i* shown as mounted to travel around rollers *j*, *j*², *j*³, is provided. Said belt may have teeth *i*² to regulate the feeding of the rollers to the cage *a* through the slot *b*². As shown the rollers *j*, *j*² may be carried by a bracket or plate *k* secured to the support *b* by means of studs *l* around which are fitted compression springs *m*. The roller *j*³ is carried by a slide *n* mounted in an extension *o* and adapted by means of a spring *p* and nuts *q* to hold the belt *i* in tension.

What I claim and desire to secure by Letters Patent of the United States is:—

1. For grinding antifriction rollers the combination with grinding means of a rotary cage for supporting the rollers and means for automatically removing and returning the rollers to the cage with their axes reversed during each revolution of the cage.

2. For grinding antifriction rollers the combination with grinding surfaces of a loosely mounted roller supporting cage provided with lateral openings adapted to separate and guide the rollers with their axes disposed radially to the center of the cage between the grinding surfaces, means for maintaining the rollers in said cage when not in contact with the grinding surfaces and means for removing and returning the rollers to the cage with their axes reversed during each revolution.

3. For grinding antifriction rollers the combination with grinding means of a rotary cage adapted to separate and guide the rollers with their axes radially disposed to the center of the cage between grinding surfaces whereby they may be rotated about their axes as well as carried around by the rotary movement of the cage, and means for removing the rollers from the cage and returning them with their axes reversed during each revolution of the cage.

4. For grinding antifriction rollers, the combination with grinding means of a rotary cage adapted to support the rollers between opposed grinding surfaces and means

comprising a twisted conduit for transferring the rollers to and from the cage during each revolution.

5. A machine for grinding antifriction rollers comprising a rotary cage, means for supporting said cage, means comprising a guide for maintaining the rollers in position, means comprising a support provided with openings and inclined projections whereby the rollers will be caused to leave and reenter the cage at each revolution of the cage, and a twisted conduit intermediate of said openings adapted to reverse the direction of the roller axes during the passage of the rollers therethrough.

6. For grinding antifriction rollers, the combination with a grinding disk, of means for supporting a series of rollers in spaced relation while moving relatively to and in grinding relation to said disk, and means for automatically reversing each roller relative to the supporting means, for the purpose described.

7. For grinding antifriction rollers, the combination with a grinding disk, of a rotary cage mounted eccentrically relative to the grinding disk and adapted to support a series of rollers in grinding relation to the disk as it rotates, and means coöperating with the cage at one side of the grinding disk for removing and returning the rollers thereto successively and automatically reversing each roller axially during such transfer.

8. For grinding antifriction rollers, the combination of a rotary grinding disk, a rotary cage mounted eccentrically relative to the disk and adapted to support a series of rollers in spaced relation and against the disk as it rotates, and means for removing the rollers from and returning them to said cage at points out of contact with the grinding disk, the rollers being automatically reversed axially during such transfer.

9. For grinding antifriction rollers the combination of a relatively stationary disk, a grinding disk, a rotary cage supported on the stationary disk, between said disk and the grinding disk, said cage being arranged eccentric to the grinding disk and adapted to support a series of rollers in spaced relation, and means for removing rollers from and returning them to the cage at points beyond the periphery of the grinding disk the rollers being automatically reversed axially during such transfer.

JOHN BASS.
